BROOM HOLDER

William Wynne Jones, Miami, Fla.

Application July 24, 1937, Serial No. 155,546

2 Claims. (Cl. 24—257)

This invention relates to a broom holder and it is one object of the invention to provide a holder of such construction that it may be secured against a wall or door and serve very effectively to grip the handle of a broom or mop and thus cause the broom or mop to be suspended in such a position that it will not rest upon the floor. It will thus be seen that a broom or the like may be suspended where it will be out of the way and in addition so supported that the broom straws will be prevented from being distorted and the shape of the broom spoiled by resting upon a floor.

Another object of the invention is to provide a device of this character of such construction that a broom handle may be thrust upwardly through an opening in the device and then firmly gripped and the broom supported in the elevated position with respect to a floor.

It is another object of the invention to provide
20 a broom holder which may be stamped from sheet
metal and thus cheaply made and in addition
have resiliency which will permit the gripping lip
along the lower edge of the handle-receiving
25 opening to firmly grip the broom handle when
the holder is flexed downwardly by the weight of
the broom.

The invention is illustrated in the accompanying drawing, wherein

Figure 1 is a perspective view showing a broom holder of the improved construction mounted in position for use and a broom suspended by the holder.

Figure 2 is a sectional view taken longitudinally through the holder along the line 2-2 of Figure 1, and

Figure 3 is a view of the blank from which the holder is formed.

This improved broom holder is formed from a sheet metal blank illustrated in Figure 3 and resilient metal is used in order that, when the broom holder is in use and secured against a wall or door as shown in Figures 1 and 2, it may be flexed downwardly by the weight of a broom and returned to its normal position when the broom is removed from the holder. The body portion 1 of the holder has been shown rectangular in shape but it is to be understood that it is not restricted to this outline. At one end there has been formed openings 2 through which securing screws or equivalent fasteners 3 are passed in order that the holder may be secured against a door or against a strip of wood 4 mounted in any desired manner against a wall of a kitchen or other room. Adjacent the end formed with the fastening receiving openings, the blank of sheet metal from which

the holder is formed is bent along the dotted line 5, thus providing the holder with an attaching portion 6. This attaching portion 6 extends in such angular relation to the body portion of the holder that, when it is secured flat against the strip 4, the body portion of the holder will project outwardly from the mounting strip at a downward incline, as clearly shown in Figure 2. An opening 7 is formed near the outer free end of the holder of sufficient size to permit the handle of a broom 8 to be freely slid through the opening into and out of position to be suspended by the holder. This opening 7 has a wide straight cut lower end or outer end and tapers towards its upper end or inner end, as clearly shown in Figures 1 and 3, in order that, when the broom handle is thrust upwardly through the opening and then released, the tapered inner end portion of the opening will cause the broom to be urged towards the gripping lip 9. This gripping lip 9 is formed by extending the side edges of the opening beyond the outer end thereof, as shown at 10, and then bending the lip downwardly along the dotted line 11. The lip will, therefore, be disposed at a downward incline across the outer end of the opening, as shown in Figure 2, and from an inspection of this figure, it will be readily appreciated that, when the broom handle is thrust upwardly through the opening 7 and then allowed to move downwardly, the body portion of the broom holder will be flexed downwardly and the edge of the lip thrust into gripping engagement with the broom handle. Brooms having handles of various lengths may, therefore, be passed upwardly through the opening of the broom holder and firmly gripped so that the broom will be maintained out of contact with the floor and distortion of the broom straws caused by the weight of a broom resting upon a floor will be prevented. While it has been stated that the device is particularly adapted for supporting a broom, it will be understood that it may be used for holding mops, rakes, and other implements having handles which may be passed through the opening of the holder. When it is desired to remove a broom, upward pressure will be applied to the outer free end of the holder to move the holder into a position which will permit the broom handle to be easily slid downwardly out of the opening.

Having thus described the invention, what is 50

claimed as new is:

1. A device of the character described comprising a body formed of resilient metal and being bent in spaced relation to one end to form an attaching portion adapted to be secured flat against 55

a support and mount the body in position to extend outwardly at a downward incline from the support, the body being formed near its outer free end portion with an opening tapered towards its inner end, the side edges of the opening being extended towards the outer end of the body to form slits, and the material between the slits constituting a gripping lip bent to extend downwardly at a rearward incline into position to have gripping engagement with an implement handle when the implement handle is passed upwardly through the opening and the body flexed downwardly by weight of the implement.

2. A device of the character described comprising a resilient body adapted to be secured at its inner end to a support and extend outwardly at a downward incline from the support, said body being formed with a handle-receiving opening, the side edges of the opening being extended towards the outer end of the body to form slits, and material between the slits forming a gripping lip extending across the outer end of the opening and bent to extend inwardly in position to grip a handle when a handle is passed upwardly through the opening and the body flexed downwardly.

WILLIAM WYNNE JONES.
